UNITED STATES PATENT OFFICE.

PERCY FRENCH JAMIESON, OF BATAVIA, OHIO.

TELEGRAPHY.

SPECIFICATION forming part of Letters Patent No. 394,697, dated December 18, 1888.

Application filed September 24, 1888. Serial No. 286,158. (No model.)

To all whom it may concern:

Be it known that I, PERCY FRENCH JAMIESON, of Batavia, in the county of Clermont and State of Ohio, have invented new and 5 useful Improvements in Telegraphy, of which the following is a specification, reference being had to the annexed drawings, forming a part thereof, in which—

Figure 1 is a side elevation of my improved 10 telegraph-key, showing the relay, battery, and sounder diagrammatically; and Fig. 2 is a front elevation of my improved telegraph-key, partly in section.

Similar letters of reference indicate corresponding parts in both figures.

The object of my invention is to provide a 15 telegraph system in which the key used in sending messages will automatically close the circuit as soon as released by the operator, thereby avoiding the necessity of switches 20 and the inconvenience arising from leaving the line open.

My invention consists in the construction and arrangement of the parts, as will be herein- 25 after fully described and specifically claimed.

In carrying out my invention I employ a 30 key similar to an ordinary telegraph-key, but arranged to make and break the circuit on the back contact, so that the circuit is always closed for the spaces and opened for the 35 intervals representing the dots and dashes of the signal or character, and I connect therewith relays in which the electrical contact is removed from the front of the relay-arm to 40 the rear thereof, so that when the circuit is opened by the key it is closed by the relay, thereby giving in the local circuit impulses 45 which cause the message to be delivered direct by the sounder.

The key-lever A is provided with a trunnion, B, which turns in bearings in the screws a b, the bearing in the screw a being of insulating material to prevent the current from passing through the said screw to the key. 50 The key carries, forward of the trunnion, a contact-piece, c, of insulating material, which strikes upon the ordinary anvil, d, when the key is depressed. The rear end of the key A is provided with an electrical contact-screw, e, which is capable of striking the anvil f.

The base C of the key supports the ears g

g', in which are inserted the screws a b, the said ears being insulated from the base. The leg D communicates electrically with the base C. The leg D' is insulated from the base C 55 and is connected electrically with the ear g' by the conductor h.

The relay E, which is placed in the line-circuit, is of the usual construction, with the exception of the replacement of the front contact with a plug, i, of insulating material, and arranging the electrical contact j with the back of the armature-lever K. The local sounder F is also of the usual construction, and is connected with the local battery G and relay E in the usual way. The leg D of the key is connected with the line-wire H, and one terminal of the relay E is connected with the ground or with a return-wire. The spring l is electrically insulated from the key, and the 60 bearings of the trunnions of the key are preferably made of insulating material. When the key is depressed, the line-circuit is broken between the contact-screw e and anvil f, thus allowing the armature-lever K of the relay to 65 fall back and complete the local circuit, causing the sounder F to make a downstroke. When the key is released, the spring l raises the forward end thereof and brings the screw e into contact with the anvil f, thus completing the local circuit and causing the armature-lever K of the relay E to be drawn forward, breaking the local circuit, and thus permitting the sounder F to make a back-stroke.

Having thus described my invention, I claim 85 as new and desire to secure by Letters Patent—

1. The combination, with the base C, having forward and rear anvils, d f, the legs D D', the latter leg being insulated from the base, 90 and ears g g', insulated from the base and provided with screws a b, and the conductor h, leading from ear g' to the leg D', of the key-levers A, having trunnions B journaled in the said screws and insulated from the 95 screw a, the forward contact-piece, c, of insulating material, the electrical contact screw e at the rear end of the lever, and the spring l between the key and base and insulated from the key, substantially as set forth.

2. A telegraph system consisting in a key 100 comprising a base, C, having front and rear

anvils, *d f*, the legs *D D'*, the latter being insulated from the base, the ears *g g'*, insulated from the base and provided with screws *a b*, the former having an insulating-bearing, the conductor *h*, leading from ear *g'* to leg *D'*, the key-lever *A*, having trunnions *B* journaled in the screw-bearings, the forward contact-piece, *c*, of insulating material, the electrical contact-screw *e* at the rear end of the lever, the insulated spring *l*, the relay *E*, hav-

ing its front contact formed of a plug, *i*, of insulating material, and having the electrical contact *j* with the back of the armature-lever *K*, the local sounder *F*, and battery *G*, electrically connected in the usual way, substantially 15 as set forth.

PERCY FRENCH JAMIESON.
